CLAIM

The ornamental design for an endoscopic medical device, as shown and described.

DESCRIPTION

FIG. 1.1 is a perspective view of an endoscopic medical device showing my new design.

FIG. 1.2 is a front view thereof;

FIG. 1.3 is a back view thereof;

FIG. 1.4 is a left view thereof;

FIG. 1.5 is a right view thereof;

FIG. 1.6 is a top view thereof; and

FIG. 1.7 is a bottom view thereof.

The broken lines in the figures show portions of the endoscopic medical device which form no part of the claimed design.

1 Claim, 7 Drawing Sheets
